United States Patent [19]

Sugano et al.

[11] Patent Number: Des. 312,249

[45] Date of Patent: ** Nov. 20, 1990

[54] ELECTRONIC COMPUTER

[75] Inventors: Yoshihiko Sugano; Tabuchi Masahiko, both of Tokyo, Japan

[73] Assignee: Kabushiki Kaisha Toshiba, Kanagawa, Japan

[**] Term: 14 Years

[21] Appl. No.: 106,768

[22] Filed: Oct. 13, 1987

[30] Foreign Application Priority Data

May 15, 1987 [JP] Japan 62-18844

CLAIM

The ornamental design for an electronic computer, as shown and described.

DESCRIPTION

FIG. 1 is a top, front, right side perspective view of an electronic computer showing our new design, the floppy disc being shown in broken lines for illustrative purposes only and forming no part of the claimed design;
FIG. 2 is a front elevational view thereof;
FIG. 3 is a left side elevational view thereof;
FIG. 4 is a rear elevational view thereof;
FIG. 5 is a top, front, right side perspective view thereof, showing the display panel in the closed position and the handle extended;
FIG. 6 is a right side elevational view thereof;
FIG. 7 is a top plan view thereof, and
FIG. 8 is a bottom plan view thereof.
